UNITED STATES PATENT OFFICE.

IRVING M. COTTRELL, OF WEST SOMERVILLE, AND GEORGE BIMBER, OF EAST BOSTON,
MASSACHUSETTS.

SILENCER FOR EXHAUST-PIPES.

1,059,279.

Specification of Letters Patent. Patented Apr. 15, 1913.

Application filed June 26, 1912. Serial No. 706,011.

To all whom it may concern:

Be it known that we, IRVING M. COTTRELL and GEORGE BIMBER, citizens of the United States, residing, respectively, at West Somerville and East Boston, in the counties of Middlesex and Suffolk, respectively, State of Massachusetts, have invented new and useful Improvements in Silencers for Exhaust-Pipes, of which the following is a specification.

Our invention relates to a silencer or muffler adapted to be attached to the exhaust pipe of an engine or some such device, the primary object being to provide a device of the character described which is simple in construction, occupies a very small amount of space, and is so constructed as to practically eliminate vibration due to the force of the exhaust.

20 The invention consists of the features of construction, combination and arrangement of parts, hereinafter fully described and claimed, reference being had to the accompanying drawing, in which:

25 Figure 1 is a fragmentary front elevation of an exhaust pipe showing the device attached thereto. Fig. 2 is a longitudinal sectional view taken on the line 2—2 of Fig. 1. Fig. 3 is a detail perspective view 30 of one of the fixed cones. Fig. 4 is a similar perspective view of one of the movable cones.

In the drawing, 1 designates the hollow, cylindrical body of the silencer which is 35 provided at its ends with external screw threads adapted to receive the couplings 2 and 3 which connect the same in the exhaust pipe line. A hollow, truncated cone 4 provided at its edges with a peripheral flange 5 is adapted to be positioned within 40 each end of the silencer body so that the said flange engages the edge thereof. The end wall 6 of each of these fixed cones is provided with a threaded opening 7 adapted 45 to receive one threaded end 8 of a longitudinally extending, centrally disposed bearing pipe 9 which connects the two cones to secure the same in fixed position against the ends of the body 1. Each of the fixed cones 50 is provided adjacent its flanged edge with a cut-away portion 10 for the reception of the point of an adjusting spanner which is used in removing or tightening the same. Each of the said cones is further provided 55 with a plurality of parallel, longitudinally

extending perforations 11 through which the exhaust gases pass in their travel through the silencer body. Adjacent the inner end of each fixed cone, a pair of movable cones 12 and 13 are mounted upon the bearing tube 9 with the latter passing through openings 14 and 15 in the end walls 16 and 17, respectively, to the said cones. The free edges 18 and 19 of the cones closely abut each other, and the reduced end 17 of the cone 13 also abuts the reduced end of the adjacent fixed cone. The cone 13 has a plurality of parallel, longitudinally extending perforations 20 provided in its tapering side wall, and which are out of alinement 70 with the perforations in the adjacent fixed cone. The innermost cone 12 of each pair of movable cones is provided with a plurality of similar perforations 21 which are also out of alinement with the perforations 75 in the coacting cone 13. A helical spring 22 surrounds the central portion of the bearing tube 9 in interposed relation to the two innermost movable cones 12, so as to normally maintain the said cones in separated position with respect to each other and in closely abutting position with respect to their coacting cones 13, the latter being thus held in engagement with the fixed cones 4.

In the operation of the device, it will be 85 seen that upon the passage of exhaust gas into the silencer body through either end thereof, the said gas will pass through the perforations in the fixed cone at that end of the body and will then become rapidly diffused as it passes through the non-alining perforations in the movable cone and the fixed cone in the other end of the body. As the gas passes through the body it will force the movable cones adjacent the end which it 90 enters toward the opposite end of the body against the action of the extensile spring. The degree of slidable movement of these movable cones will depend upon the force of the exhaust. In practice it has been found 95 that the force of the exhaust is completely diffused without causing great vibration of the parts of the device, they being constructed of comparatively heavy metal, and further that there is very little back pressure 100 due to the large number of perforations in the cones, and to the fact that they extend parallel to the longitudinal axis of the body.

What is claimed is:

1. A device of the class described comprising

110

- ing a hollow cylindrical body, and a plurality of cone-shaped baffle members provided therein and having longitudinally extending perforations.
5. 2. A device of the class described comprising a hollow cylindrical body, and a plurality of cone-members positioned therein and having longitudinally extending, non-aligning perforations.
10. 3. A device of the class described comprising a hollow cylindrical body, a plurality of cone members slidably mounted therein, and means engageable centrally with said members for guiding the same during movement.
15. 4. A device of the class described comprising a hollow cylindrical body, a guide member positioned within said body, and a plurality of cone members slidably mounted upon said body.
20. 5. A device of the class described comprising a hollow cylindrical body, a guide member disposed within said body, a plurality of cone members slidably mounted upon said guide member, and means tending to maintain the innermost pair of cone members in separated position.
25. 6. A device of the class described comprising a hollow cylindrical body, a guide member positioned centrally within said body, a plurality of cone members slidably mounted upon said guide member, and means carried by said guide member for normally maintaining the central pair of cone members in separated position.
30. 7. A device of the class described comprising a hollow cylindrical body, a fixed
- cone member disposed within each end of the said body, means on each of said cones for limiting the forward movement thereof, 40 a bearing tube detachably secured at its ends to said cone and extending longitudinally and centrally with respect to the said body, a plurality of movable cones slidably mounted upon said tube, and resilient means carried by said tube for normally maintaining said movable cone in extended position.
8. A device of the class described comprising a hollow, cylindrical body having its ends open, a fixed perforated cone projecting into said body through each of its ends, and a plurality of perforated cones slidably mounted within said body.
9. A device of the class, described comprising a hollow cylindrical body having 55 its ends open, a perforated, hollow cone fixedly mounted in each end of said body, a centrally disposed, longitudinally extending bearing tube having its ends detachably secured to each of said fixed cones, a pair of 60 perforated, hollow cones disposed adjacent the inner ends of each fixed cone and slidably mounted upon the said tube with their free edges abutting each other, and resilient means for normally maintaining said pairs 65 of movable cones in spaced relation with respect to each other.
- In testimony whereof we affix our signatures in presence of two witnesses.
